HAT OR THE LIKE

David P. Litwin, Los Angeles, Calif.

Application May 22, 1950, Serial No. 10,089

Term of patent 3½ years

(Cl. D3—13)

To all whom it may concern:

Be it known that I, David P. Litwin, a citizen of the United States, residing at Los Angeles, Los Angeles County, State of California, have invented a new, original, and ornamental Design for a Hat or the like, of which the following is a specification, reference being had to the accompanying drawings, forming a part hereof.

Fig. 1 is a plan view of a hat showing my new design as it appears in undraped position.

Fig. 2 is a vertical sectional view thereof taken on the line 2—2 of Fig. 1.

Fig. 3 is a front perspective view thereof as it appears in wearing position, and

Fig. 4 is a rear perspective view thereof as it appears in wearing position.

I claim:

The ornamental design for a hat or the like, as shown.
